UNITED STATES PATENT OFFICE.

ADDISON G. WATERHOUSE, OF NEW YORK, N. Y., ASSIGNEE, BY MESNE ASSIGNMENTS,
TO ATLAS STILL MFG. CO., OF NEW YORK, N. Y., A CORPORATION OF NEW YORK.

DISTILLING APPARATUS.

1,113,521.

Specification of Letters Patent.

Patented Oct. 13, 1914.

Original application filed March 13, 1909, Serial No. 482,884. Divided and this application filed October 31, 1910. Serial No. 589,851.

To all whom it may concern:

Be it known that I, ADDISON G. WATERHOUSE, a citizen of the United States, and resident of New York city, borough of Richmond, in the county of Richmond and State of New York, have invented certain new and useful Improvements in Distilling Apparatus, of which the following is a specification.

10 This application is a division of my application for patent on method of distilling, filed March 13, 1909, Serial No. 483,334, now Patent 991,570, May 9, 1911, and relates to means set forth in the same for distilling
15 and rectification of volatile products, such as alcohol, at one operation and in an automatic and continuous manner.

My invention comprises novel details of improvement and combinations of parts that will be more fully hereinafter set forth and then pointed out in the claims.

Reference is to be had to the accompanying drawings forming part hereof, wherein,

Figure 1 is a sectional elevation of an apparatus embodying my invention; Fig. 2 is a horizontal section of the apparatus substantially on the line 2, 2, in Fig. 1, and Fig. 3 is a central section of Fig. 2. Fig. 1 shows diagrammatically and partly in section an apparatus comprising a supply pipe A, a heat exchange B, a heater or evaporator C, a boiler D, a condenser E, and analyzing columns F and G.

The heat exchange B, which may be of any suitable form, is shown as a closed vessel having two separate compartments formed by partitions adapted for transferring heat by conduction from one compartment to the other, into one of which compartments the supply of fresh liquid, such as fermented worts, enters at its lower extreme through pipe A, and then through a stuffing box and nipple B', into a lower chamber B², whence it ascends through a number of parallel tubes B³, into an upper chamber B⁴, whence it continues through a valve B⁵, which normally remains closed until opened subject to certain conditions to be hereafter described.

50 The conditions under which the valve B is opened are, among other things, such as to permit of the flow of liquid through the heat exchange as stated, and also such as to cause a corresponding volume of hot exhausted

liquid or worts to flow from the boiler through pipe B^b , and enter the upper part of the outer shell of the heat exchange B , outside of tubes B^a , whence it will slowly descend until it is finally discharged from the shell at its lower extreme, and out through the discharge pipe B^g . In this way the out-flowing hot and exhausted liquid which descends within the shell of heat exchange B and outside of tubes B^a , transfers its heat, by conduction, to the cold fresh liquid which is at the same time ascending tubes B^a , so that by the time the hot liquid descends from the top to the bottom of the heat exchange it will be discharged in a relatively cold state, while the relatively cold inflowing liquid which enters the bottom of the heat exchange will become hot or heated by the time it has ascended to the top thereof, thereby causing the heat transferred to the inflowing liquid to be returned to the apparatus and used over and over again. The thus heated fresh liquid after being allowed to pass the valve B^d , ascends through pipe B^e , into a chamber C' shown in annular form, which comprises part of evaporator C . This evaporator is shown partly in section in Fig. 2, wherein one of the outer flanges C^2 is provided with a central floor C^3 , having an outer cylindrical shell or wall C^4 , and an inner concentric wall C^5 , which walls are connected by a radial partition C^6 . The bottom or floor C^3 of annular chamber C' , is provided with a series of heating tubes C^7 , C^8 , extending into boiler or receptacle D , through which tubes liquid can flow successively, as by flowing into and then out of one tube, and then into and through the next tube, and so on until the liquid has entered into and flowed from each tube without escaping from chamber C' . The liquid, as stated, enters chamber C' , through the pipe B^e , and then flows around through the chamber C' , but in so doing enters and flows from each of the heating tubes or passages C^7 , until the liquid is discharged through a pipe C^8 placed at the further extreme of the chamber C' , beyond the inlet pipe B^e . I have shown pipe C^8 opening into boiler D . An inner well C^{10} is shown formed by the floor C^3 and concentric wall C^5 . In wall C^5 an opening C^{11} is shown, which allows liquid, as it enters through the pipe B^e , to flow from any determined

part of the chamber C', into the well C¹⁰, and also allows the same liquid, or more liquid which may accumulate in the well as the result of condensation, to flow back from the well into chamber C', whence it will follow the course of the liquid on its way around chamber C', as described, until it is discharged through the open part of pipe C⁸. The lower ends of tubes C⁷ are closed, their upper open ends communicating with chamber C'. Inside of each heating tube C⁷ is a circulating pipe C¹², which is open at both ends, its purpose being to assist the circulation of liquid through tubes C⁷ by offering a passage for the cooler liquid to descend within pipe C¹² from chamber C', and take the place of other liquid as it tends to rise in the outer tube C⁷ after being brought to a higher temperature by the heat transmitted to it within boiler D through the tube C⁷. Other means may be employed for causing such circulation of liquid, such as by forming a continuous passage by a series of pipes connected by return bends.

The evaporator C, being connected to the boiler, as by flange C², provides a closed boiler, so that whatever steam or vapor is generated in the boiler, in order to escape, must pass out through the side pipe E⁴, and then up into the condensing column E, as hereinafter described. The evaporator C is also covered and made a closed vessel by means of the plate C¹⁴, which is bolted to flange C¹⁵, so that all the vapor generated from the liquid flowing through the evaporator C is compelled to pass up through opening C¹⁶, in the plate C¹⁴, and then into the analyzer column F, that communicates with opening C¹⁶, the further action of which vapor will be explained. The liquid discharged into the boiler D from or through the vaporizer or evaporator C would soon fill or overflow the former, and to prevent this and maintain a predetermined liquid level in the boiler a float D' is provided, which will be supported on the surface of the liquid and rise and fall with it, as the surface of the liquid changes from any predetermined level, such as represented by the dotted line W. To this end float D' is shown connected by rod D², to a pivoted lever D³, which opens or closes discharge valve D⁴, controlling the passage through pipe D⁶, serving to keep the liquid at the level required.

Heat may be applied to boiler D in any way known to the art, but which in the present case is represented by the gas burner H. This heat applies to the liquid which has been discharged into boiler D, and such heat is conducted to the fresh liquid while it is passing through evaporator C, and circulating in the tubes C⁷.

One of the leading objects of this inven-

tion is to limit the temperature to which the liquid in boiler D can be raised, so that such temperature will not exceed that which is just sufficient for driving substantially all of the alcoholic or desired vapor from the worts or other liquid without generating any more steam or aqueous or other vapor from it than is possible. To effect this a thermal regulator is used and adjusted for operating the admission valve B⁵, so that at approximately the temperature desired fresh liquid will be allowed to flow through valve B⁵, pipe B⁴, and evaporator C, into boiler D, as fast as, but no faster than, the applied heat can maintain the temperature which effects this flow. To accomplish this a thermostat or heat actuated regulator is shown, submerged in or placed in thermal communication with the liquid in the boiler, the temperature of which is to be limited. The regulator shown comprises a tube or feeler D⁸, closed at its free end and in open communication with a recess D⁶, closed by a flexible diaphragm or movable member D' adapted to be actuated by a pressure created by the heat of the liquid in the boiler acting upon some volatile fluid confined within feeler D⁸, and recess D⁶, whereby a determined temperature of the liquid in the boiler will produce motion of the diaphragm D', which is transmitted to valve B⁵, through valve stem B⁷, in a way which will overcome the resistance of its spring B⁸, and open valve B⁵, to an extent which will permit the flow of fresh liquid in the boiler as fast as the applied heat can maintain its temperature at approximately the point stated and no faster.

Heretofore, in distilling alcohol in a continuous manner, the richer or fresh worts or solutions fed into the still have been weakened or diluted by being fed into the exhausted liquid so that a much higher temperature is required to separate the alcohol in its weakened state, from such diluted liquid, than would have been required at first or before it had been so diluted, and this higher temperature results in generating a larger percentage of steam or aqueous vapors, as well as those of fusel oils, which are objectionable and should be avoided. Again, in allowing alcoholic vapor which has been generated to come into contact with liquid that is cooler than the vapor, much of such vapor is condensed by contact with such liquid and carried back to the diluted solution, from which it must be redistilled in a way which entails a greater use of heat and encumbers the still with an increased percentage of objectionable vapors which are difficult to separate from those desired.

The foregoing objections become apparent when it is observed that the temperature required for driving alcoholic vapor from an aqueous solution varies, as, for example,

with a solution of 90 per cent of alcohol, its vapor will start at about 171° Far., in a 25 per cent. solution its vapor will start at about 187° Far., and from one per cent. solution the alcoholic vapor will start at about 210°, and be completed before the boiling point of water is reached.

By my invention the above objections are to a great extent avoided, by means of progressive increments of heat applied to the solution as it becomes weakened in alcoholic properties, (which increments of heat result from the period of time it takes the liquid to pass through the apparatus), so that the alcoholic vapor will be generated progressively at the minimum temperature under which it can be driven from the continually weakening solution, and conducted from the solution and condensed, so that the alcoholic vapor will not return to and be condensed by contact with liquid which is cooler than the liquid from which said vapor was driven. These results are effected as follows: As the fresh liquid rises through the heat exchange B the heat from the hot liquid being discharged in thermal communication with such fresh inflowing liquid causes the formation of alcoholic vapor from such fresh liquid, which vapor with its liquid continues up through the heat exchange and then through valve B⁵, and pipe B⁶, into the evaporator C, where the vapor passes over the surface of the liquid circulating around the chamber C', (which liquid is continually rising in temperature) until such vapor passes up into the analyzer F, then as the liquid flows around the evaporator and circulates in each of the tubes as described, the liquid in the tubes C' absorbs heat both from the steam and vapor generated in the boiler, and which is above the liquid therein, as well as the heat which is directly applied to the liquid in the boiler, thus continually increasing the heat of the advancing liquid as the alcohol which it contains grows less in percentage, so that the vaporization of the alcohol takes place at the lowest practicable temperature. Now, the alcoholic vapor which these increments of temperature create, will not flow backward to the cooler and succeeding liquid which would cause its condensation, because the first vapor generated is flowing from that direction, so that it with succeeding vapor crowds onward over the surface of liquid which is constantly growing hotter, until all the vapor from the liquid is forced up through the opening C¹⁶, in plate C¹⁵, and then upward through the analyzer column F. When the exhausted liquid from which most of the alcohol has been extracted during its passage through the evaporator C is discharged into the boiler D, as described, it is therein raised to the limit of temperature to be imparted to such liquid,

which increase of temperature drives substantially all of the remaining alcoholic vapor from such liquid, and with such vapor more or less aqueous and fusel oil vapors are or may be carried, which latter are mostly condensed after passing through the side pipe E⁴ into column E, while the alcoholic vapor continues on through connecting pipe E' into the top of the analyzing column F. The condensates, which are mostly water, and which form in the condensing column E, and in the analyzing column F and in column G, are disposed of as follows: the drain tube E² leads that condensate which forms in column E back to evaporator C, while that which forms in column F returns to evaporator C, by gravitation, and that which forms in analyzing column G returns to evaporator C through the drain tube G². The columns adapted for arresting aqueous vapors and allowing the alcoholic vapors to continue to a final condenser, to be connected with pipe G³, (which are not necessary to be shown) are herein represented as cylinders E, F and G, which may be of any desired length, or increased in number, and joined in series as the columns F and G are joined by means of the connecting pipe G'. Such columns may be formed in any way known to the art and used for performing the condensing, analyzing or rectifying work of a still. A gas burner H may be placed under boiler D, and this burner may be supplied with gas from any permanent source through the gas pipe H', but so that it will only supply a limited amount of gas, or just sufficient for operating the still slowly, and not under any conditions to rush it beyond its minimum capacity. An auxiliary fuel pipe H² leads to the burner H from the analyzer column G or other suitable part of the still; and supplies fuel either in the form of vapor or a condensate from the still, so that the fuel furnished through pipe H² will cause more or less heat to be produced from the burner H, and this more or less heat will be such as to rush or retard the working of the still in ways which will automatically govern its action to that which will be to its best working advantage, although the pipe H² may be dispensed with if desired.

While I have shown the gas burner H it will be understood that the still may be heated by any suitable means.

Having now described my invention what I claim is:—

1. A distilling apparatus comprising a vaporizing chamber, a receptacle communicating therewith to receive discharge liquid therefrom, a thermal actuator in thermal relation to the discharge liquid, and means controlled by the thermal actuator to regulate the flow of liquid through the still.
2. A distilling apparatus comprising a

- chamber having an inlet and an outlet spaced apart, tubes communicating with said chamber between the inlet and the outlet to receive liquid from said chamber, a receptacle to receive discharge liquid from said chamber, a thermal actuator in thermal relation to liquid in said receptacle, and means controlled by said actuator for regulating the flow of liquid to said chamber.
10. 3. A distilling apparatus comprising a chamber having an inlet and an outlet, tubes spaced apart and communicating with said chamber between said inlet and outlet to receive liquid from said chamber, a casing containing said tubes, means to apply a heating fluid in said casing to said tubes, and a thermal actuator in thermal relation to liquid discharged from said chamber to control the flow of liquid through the still.
15. 4. A distilling apparatus comprising a chamber, means to supply liquid to and discharge it from said chamber, tubes communicating with said chamber to receive liquid therefrom, said chamber having a vapor out-
- let, a condenser communicating therewith, a receptacle, means to discharge liquid from the chamber to said receptacle, a thermal actuator in thermal relation to discharge liquid in said receptacle, and means controlled by said thermal actuator for regulating the flow of liquid through said chamber and receptacle.
20. 5. A distilling apparatus comprising a chamber, means to supply liquid to and discharge it from the chamber, tubes spaced apart and at their upper ends communicating with said chamber to receive liquid therefrom, a receptacle below said chamber inclosing said tubes and communicating with said discharge from said chamber, a condenser communicating with said receptacle.

Signed at New York city, in the county of New York, and State of New York, this 28th day of October, A. D. 1910.

ADDISON G. WATERHOUSE.
